(57) **CLAIM**

The ornamental design for a lighting fixture component, as shown and described.

DESCRIPTION

FIG. 1 is a bottom perspective view of a lighting fixture component depicting a new design;

FIG. 2 is a top perspective view thereof;

FIG. 3 is a front elevation view thereof;

FIG. 4 is a back elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a bottom perspective view thereof including environmental structure; and,

FIG. 10 is a top perspective view thereof including environmental structure.

The broken line disclosures in FIGS. 9 and 10 represent environment which forms no part of the claimed design. The remaining broken line disclosures in the views represent portions of the lighting fixture component that form no part of the claimed designs.

1 Claim, 10 Drawing Sheets
